UNITED STATES PATENT OFFICE.

FRIDOLIN E. BERSCHE, OF WATERLOO, ILLINOIS.

RADIOCLOCK.

Application filed September 23, 1927. Serial No. 221,510.

The present invention relates to an improved radio clock and it has more particular reference to a structure of this class which embodies an alarm clock work in which a novel and dependable electric circuit make and break device is incorporated.

Briefly, the invention comprises a clock-work such as is employed in the construction of ordinary alarm clocks, means whereby it 10 can be mounted upon the radio cabinet in such a way as to render it accessible in order that the hands on the main dial can be set or the alarm set to go off at a predetermined time.

15 Associated with the rotary alarm shaft is an electric circuit maker and breaker of a manually controlled type which may be regulated to cause the radio set to automatically start at a predetermined time, or to stop 20 when desired. Thus, a definite program can be had whenever desired.

My principal aim is to provide a mechanism of this character which is so constructed as to permit it to be incorporated in the ordinary clockwork without requiring alteration 25 of any of the existing parts, with the exception of removing the impact element and signal and substituting for the impact element, a rotary device including manually 30 regulated make and break pins.

Other advantages can better be appreciated after reading the following description and the accompanying drawings.

In the drawings:—

35 Figure 1 is a fragmentary front elevational view of a portion of the cabinet showing the radio clock mounted therein.

Fig. 2 is a horizontal section through the cabinet, looking on top of the complete structure as it appears inside of the cabinet.

40 Fig. 3 is a side elevational view of the clock work removed from the cabinet.

Fig. 4 is a view showing the stationary current supply brush.

45 Fig. 5 is a perspective view of certain of the details.

As before indicated, I employ an ordinary clock work such as is used in the construction of a conventional alarm clock, and in the 50 drawings, I have designated the frame of this clock work by the reference character 6.

In carrying out the invention, this frame is suitably mounted upon a swingable closure 7 (see Fig. 2), this closure being hingedly 55 mounted upon the radio cabinet 8. It is

equipped with the customary main dial with which the usual hands cooperate and with a supplemental dial indicated at 9 in Fig. 1, with which the alarm pointer cooperates.

In Fig. 2, the reference character 10 designates the key for winding the spring while the reference character 11 designates the long stem for setting the alarm. The only parts of the alarm to be specifically mentioned here, are the usual flat spring 12 (see Fig. 3) and the rotary shaft 13. In practice, this shaft carries an impact element, which cooperates with the signal. These parts are removed however, and the present invention is substituted therefor.

As shown in Figs. 2 and 3, a brass disk 14 is fastened to one end of the rotary alarm shaft 13, and is insulated from this shaft by insulating rings 15. At the center of this disk, is a post 16 upon which a rocker arm 17 is pivotally mounted. The rocker arm carries a pair of independent contact members in the form of pins 18 and 19, these pins working through holes in the brass disk 14. It will be noticed however, that the pin 19 is provided on its lower end with an insulating head 20.

With this arrangement, either one of the pins 18 or 19 may be forced down through the opening in the disk. Closely associated with the rotary pin equipped disk is a novel trip device. This device is shown in detail in Fig. 5, and its position in the clock work is better shown in Fig. 3.

As represented in the last-named figure, 90 it comprises a longitudinally shiftable rod 21 carrying a right angularly disposed arm 22 at one end. Incidentally, this arm 22 is of insulation material and on its extremity, it is provided with a right angularly extending pin 23 which cooperates with either one of the aforesaid pins 18 and 19.

Also carried by the rod 21, is an actuator 24 of right angular form. The long leg of this actuator extends through an opening in the frame of the clock and bears upon the aforesaid flat spring 12. Thus, the inside trip device comprising the parts 21, 22, 23 and 24, is movable as a unit in the frame of the clock toward and from the pins 18 and 19. 105 In connection with these parts, it will be noticed that a wire 25 is electrically connected with the pin 23 (see Fig. 4). Also as shown in Fig. 4, a current supply brush is provided. This brush comprises a socket 26 having a 110

spring pressed carbon plunger 27 located therein, the socket being mounted on a binding post 28, with which an electric conductor or wire 29 is connected.

5 The parts 27, 28 and 29 are mounted on the strip of insulation material 30 which is in turn fastened upon one of the frame bars of the clock work. Located at the remote end of this spring 30 is another binding post 31 10 with which a wire 32 is connected.

In practice, the wire 25 leads the post 31 under or along the insulated base 30. The positive wire from the storage battery is connected to post 28. Then the positive storage 15 wire of the set is connected to post 31.

In considering the operation, it is to be assumed for example, that the pins 18 and 19, are occupying the position shown in Fig. 2. At this time, insulation head 20 on 20 the pin 19, which is then pushed out, is resting against the short pin 23 of the so-called trip device. Thus the circuit is broken, even when the radio switch is turned on. Now the alarm hands can be set in a customary manner 25 to the time desired to start the radio. Incidentally, when the alarm hand is thus set the entire trip device, will be moved in a direction toward the disk 14, sliding the short pin 23 against the edge of the insulator head 20. 30 Next, the rocker arm 15 is actuated so that the right hand end in Fig. 2 is pushed down and the left hand end pushed out in the opposite direction. This causes the parts to assume a relationship just reverse to that represented in Fig. 2. This movement of the pin 35 19 however does not disengage it from the pin 23.

When the hands of the clock reach the designations on the dial corresponding with that 40 of the alarm pointer, as is usual, the alarm mechanism in the clock work causes the flat spring 12 to move in a direction away from the frame 6. In this connection, it is to be stated that persons familiar with the operation 45 of the alarm mechanism will understand that in one position, the spring 12 is substantially in contact with the frame of the clock-work, while when the alarm, ordinarily goes off, this spring moves in a direction away from the frame. Thus since the spring is connected with the trip device, of this invention, it 50 will cause this trip device to shift longitudinally, thus actuating the pin 23. In other words, the pin 23 will at one time be moved up or toward the disk 14 while at the time the alarm would go off, it moves in a direction away from it.

When it moves in the last-named manner, it 55 allows the insulator head 20 to clear the pin 23. Now, the alarm shaft 13 will rotate in the customary way under the action of the spring, turning the disk 14 to an approximate half revolution. It is remembered, however, that the pin 18 is now pushed toward the disk 14

as far as possible. Hence, it comes into engagement with the pin 23. 65

Since the pin 18 is not insulated from the pin 23, the circuit is thus closed. Also since the radio switch is already on, it is obvious 70 that the radio will start at the time which the alarm was previously set. Just the reverse is true if we had started with the pin 18 in engagement with the pin 23, instead of an engagement between the pin 19 and 23 as shown in Fig. 2. 75

For example, to assume that pin 18 has engaged the pin 23, instead of the pin 19, in Fig. 2. Then the pin 19, would have been pushed outwardly to hold the pin 18 in an opposite direction, and as soon as the alarm "would go off", the pin 18 would clear the pin 23 and the disk 14 would rotate a half revolution to bring pin 19 against the pin 23 and to open the circuit again, thus stopping the radio at a certain time. 80

It is of course obvious that by controlling the usual switch on the radio, this auxiliary time controlled switch can be thrown out of operation. The advantages, and construction and operation of the invention will be 90 clear after considering the description in connection with the drawings. Therefore, a more lengthy description is believed unnecessary. 95

Minor changes in shape, size, and rearrangement of parts coming within the field of invention claimed may be resorted to if desired. 95

Having thus described my invention, what I claim as new is:—

1. In a radio clock of the class described, a 100 clockwork embodying customary alarm mechanism including a rotary alarm shaft, a head mounted upon said alarm shaft, independently operable circuit make and break pins carried by and rotatable with said head, a spring pressed brush cooperable with the head, and a trip device mounted on the clockwork and cooperable with the alarm mechanism and including a combined stop and contact pin for successive cooperation with the pins on said head. 105

2. In a radio clock, a clockwork including an alarm mechanism having a rotary alarm shaft, an electricity conducting disk carried by and insulated from said shaft, a post on said disk, a rock arm pivotally mounted between its ends on said post, selectively operable pins pivotally mounted on the ends of said rocker arms and movable through openings in said disk, an insulating element carried by one of said pins, a current supply brush bearing against the periphery of said disk, and an alarm actuated trip device including a combined stop and contact pins cooperable with the first-named pin. 115 120 125

In testimony whereof I affix my signature.

FRIDOLIN E. BERSCHE.
